UNITED STATES PATENT OFFICE.

WILLMER D. LLOYD, OF BEAVER FALLS, PENNSYLVANIA.

CARPET AND RUG CLAMP.

1,150,046.

Specification of Letters Patent. Patented Aug. 17, 1915.

Application filed January 22, 1914. Serial No. 813,735.

To all whom it may concern:

Be it known that I, WILLMER D. LLOYD, a citizen of the United States, residing at Beaver Falls, in the county of Beaver and State of Pennsylvania, have invented certain new and useful Improvements in Carpet and Rug Clamps, of which the following is a specification.

This invention relates to carpet and rug clamps, and has for its object the production of a device with parts specially constructed and arranged for the purpose of enabling one person without assistance to suspend conveniently and quickly a rug or carpet from a rope, in order that the rug may be beaten, swept or otherwise cleaned. The particular improvement believed to be attained by the special construction herein-after disclosed consists in providing the clamp with a hook member comprising convergent portions located at the sides of the hook and separated by a distance, whereby a clothesline or the like is engaged by the hook at two points. Thus, the hook is much more securely held upon the line and does not turn and twist in the wind. By the use of this invention it is believed the line wears longer, and the hold upon the fabric is not constantly turned and twisted by the wind and finally torn out. The clamp may be easily hooked over a line, and, once so hooked is caused by the weight of the carpet or rug to grip the line and is not readily loosened by any ordinary wind, or movement to which it is liable. Furthermore, a clamp made in accordance with this invention may be attached to a rug or carpet while lying upon the floor, and the clamp affords a strong and convenient body to be grasped by the hand or hands when a relatively heavy rug is to be raised.

The special construction and arrangement of parts going to make up this invention are shown in the accompanying drawings, in which—

Figure 1 represents a side view of this invention attached to the edge of a rug, and Fig. 2 is a perspective view from the side showing this invention alone with the plates or jaws closed.

Throughout the description and drawings, the same letter is used to refer to the same part.

Considering the drawings, it will be noted

that this invention has two clamping plates 55 or jaws of which the smaller and front plate is designated by the reference letter A, and the larger and rear plate is marked B. A bolt C passes through both plates as illustrated, and the head c of the bolt lies against the outer surface of the front plate A. A thumbscrew D engaging the bolt and acting upon a washer E against the rear surface of the larger plate B, is employed to draw the two plates toward each other in the ordinary manner.

To enable the rug to be suspended from a rope F as set out in Fig. 1, this invention is provided with a hook made of relatively heavy, stiff wire. As best shown in Fig. 2, 70 the bill G of the hook extends downwardly and outwardly, and the vertical portions H and J lie against the inner surface of the rear plate B, the ends of those vertical portions of the hook being passed through the 75 plate and clenched on the back thereof as illustrated. It will be noted in Fig. 1, that the space between the bill of the hook and the vertical portions, is wide at the bottom and narrow at the top, and that the rope F 80 is held in the converging space with greater force the heavier the rug or carpet may be. The vertical portions H and J and the inclined sides of the bill G of the hook form convergent portions separated by a distance, 85 and the line is gripped thereby at separated places. The separation of the gripping points prevent the hook from constantly turning and twisting in the wind, which always wears a line, and often tears the suspended fabric.

In both the figures of the drawing it will be seen that the top of the front plate A, which is referred to by the letter a, is beveled inwardly and upwardly toward the rear plate B. The beveled end a is directly beneath the lower portion of the bill of the hook when the parts are assembled, and serves to guide the rope into the hook. This construction renders it easy for a person to 100 place the hook on the rope with one hand.

The clamping plates A and B are in practice made of wood having about the size and thickness illustrated.

An advantageous point with regard to the 105 construction of this invention, and, as best illustrated in Fig. 2, is that the upper part of the inner surface of the clamping plate A

rests against the vertical portions of the hook, and the top of the plate A is, therefore, spaced by the thickness of the wire from the rear plate B, while the lower edges of the plates come together. Thus, this invention may be used to suspend thin fabrics from a clothesline, in place of the common clothespin. It is often desirable that the piece of material to be suspended for drying or for whatever purpose shall be held at a particular point, and would be injured if an ordinary clothespin were used to bind it to the line. Where the piece of fabric held by this invention is light in weight, a slight pull upon the plates downwardly will cause the rope to jam in the convergent space of the hook mentioned, but, where the rug or carpet is heavy its own weight operates to secure the hook firmly in position upon the rope. A heavy carpet or rug cannot break or injure the hook, as the greater the weight the more strongly the vertical members H and J are pressed against the rear plate. The pull of the weight is almost in line with the vertical parts H and J and is, therefore, upheld by twice the tensile strength of the wire.

Having now described this invention and

explained the mode of its operation, what I claim is:—

A clamp comprising a front plate and a rear plate, means connecting the said plates, the rear plate being larger than the front plate and extending above it, the front plate having its upper edge beveled upwardly toward the rear plate, and a hook formed of a single piece of wire having its ends secured to the rear plate, the said hook having two vertical members spaced apart and arranged against the rear plate, and the bill of the hook having sides extending from said vertical members downwardly and outwardly over the said beveled top of the front plate and connected by a horizontal portion whereby a rope may be guided into the hook, the said vertical members and sides forming converging portions constructed to grip a rope at two separated points thereby preventing the hook from twisting upon the rope.

In testimony whereof I affix my signature in presence of two witnesses.

WILLMER D. LLOYD.
